MEAD S. CARMICHAEL, OF SPARTA, WISCONSIN

BLANCHING AND CLEANING DEVICE

Application filed March 11, 1929. Serial No. 345,958.

This invention relates to blanching devices and more particularly to article cleaning means, although certain features thereof may be employed with equal advantage for other purposes.

It contemplates more especially the provision of means for effectively removing foreign substances from edible articles without entailing much labor or subjecting the articles to injury.

Numerous devices have heretofore been proposed for cleaning articles by submersion in a water bath; however, these have not proven entirely satisfactory owing to their inefficiency and injurious effect thereon. Further, these devices are not entirely dependable, since the cleansing effect is not uniform nor free from injury to the articles, thereby necessitating keen inspection and re- processing for the purpose of satisfactorily completing the blanching thereof. With the tremendous growth of the canning industry and the increased consumption of canned articles including peas and the like, known cleaning methods have retarded the processing thereof and materially increased the cost of the product to the consumer.

One object of the present invention is to provide means for blanching or removing foreign substances from articles without entailing much labor.

Another object is to provide means for continuously withdrawing foreign substances from a cleansing fluid which is employed in a continuous blanching process.

Still another object is the provision of means for continuously skimming the surface of a cleansing fluid contra to the directional flow thereof to remove the impurities therefrom without interruption.

A further object is the provision of an endless conveyor effective to carry spaced instrumentalities thereon for coaction with a directional flow of water to remove the impurities therein.

A still further object is to provide means for directing articles along a predetermined path in the presence of water for effecting the removal of foreign substances therefrom

without interfering with the continued processing thereof.

Still a further object is the provision of means for continuously removing impurities from an article cleansing medium, and thereafter isolating the articles from the fluid without interruption to the continuous processing thereof.

Other objects and advantages will appear from the following description of an illustrative embodiment of the present invention.

In the drawings:

Figure 1 is a view in elevation of a device embodying features of the present invention, parts thereof being shown in section to clarify the illustration thereof.

Figure 2 is a fragmentary plan view of the device disclosed in Figure 1.

Figure 3 is a sectional view taken substantially along line III—III of Figure 1.

Figure 4 is a sectional view in elevation of a modified structure embodying features of the present invention.

The structure selected for illustration comprises means for confining articles to enable the selective discharge thereof along a predetermined path, these consisting, in this instance, of a plurality of hoppers 10 which have individual discharge spouts 11 through which the articles are passed at varying rates depending upon the adjustment of a slidable discharge valve 12 associated therewith. Articles requiring cleansing, in this instance peas of varying size and quality, may be supplied to the hoppers 10 so that any desired grade of article may be washed and blanched

to meet an instant requirement, thereby rendering the device capable of cleansing articles to fulfil various demands. On the other hand, however, each of the hoppers 10 may be provided with the same or different varieties of articles for discharge in an extended trough 13 which serves to guide the traverse thereof in the processing for removing the foreign particles therefrom.

The trough 13 is inclined slightly so as to effect the gravitation of the articles therealong until discharged after subjection to blanching, washing, and cleansing. To this end the trough 13 is supported in the desired

position by means of standards 14 secured thereto in any suitable manner for extension to the floor or other foundation. The troughs 13 are arranged so that parts 13' and 13'' thereof are inclined in opposite directions forming a continuous zigzag path in superposed relation to minimize the otherwise extensive floor area required therefor.

The highest point of the trough 13 receives a conduit 15 which leads to any suitable water or other cleansing fluid supply source, in this instance a pump 16, which furnishes the necessary water to the troughs 13 to maintain the articles, in this instance peas, submerged during their passage therein. The passage of the articles down the trough 13 over and near the bottom thereof incites a twirling movement to the water, thereby elevating the foreign substances for suspension therein. As a consequence, there is decided comingling of the articles with clean water during the passage thereof within the trough to effect the continuous removal of foreign substances therefrom.

It is necessary or at least highly desirable to continuously withdraw the foreign substances from the water near the terminus of its flow, thereby effecting the segregation of the articles therefrom without interrupting the continuity of cleansing. To this end, the discharge terminal of the trough 13'' communicates with a chamber 17 which has the bottom 18 thereof disposed at a greater inclination than that of the trough 13''. This causes the articles and its water carrier to pass with increased acceleration commencing with the inlet orifice 19 defined by the joiner of the chamber 17 with the terminal end of the trough 13''. As shown, the chamber 17 is provided with a passage 20 which is restricted by a wall 21 disposed in parallelism with the bottom 18. The slight retardation occasioned by this restriction will tend to create a water head in the troughs 13 which is desirable insofar as it insures the constant submersion of the articles during their passage therethrough.

The chamber 17 is supported by standards 22 and 23 which are secured to the lateral walls thereof in any appropriate manner. Spaced shafts 24 and 25 are journalled in the standards 22 and 23, respectively, to receive sprocket wheels 26 and 27 disposed within the chamber 17. An endless conveyor 28 composed of a series of flexibly associated link 29 mesh with the teeth of the sprocket wheels 26 and 27 for effecting the continued linear movement thereof responsive to the application of power to the shaft 24 which has a spur gear 24' fixed thereto for imparting rotary movement thereto. Obviously, any power source may be harnessed to the gear 24' in the customary manner.

As shown, the sprocket wheels 26 and 27 are of different diameters so that the con-

veyor 28 will traverse a path parallel to the bottom 18 of the tank 17. Angularly disposed plates 30, in this instance of rectangular contour, are secured to the links 29 of the conveyor 28 at spaced intervals for movement therewith in a path contra to the directional flow of the water in the tank 17. The plates 30 terminate in a plane parallel with the top wall 21 of the restricted passage 20 in contact therewith to skim the surface of the water directed thereagainst for effecting the withdrawal of the impurities therefrom. The clock-wise directional movement of the conveyor (viewed from Figure 1) ultimately discharges the impurities on a platform 31 which is secured to the tank 17 at the remote end 32 thereof. As shown, the plate 31 is hinged as at 33 to enable the adjustable inclination thereof owing to a bolt 34 which has one extremity thereof anchored to the plate 31 by means of a lug 35. The bolt 34 projects through a plate 36 to receive a nut 37 in threaded engagement therewith to enable the variation in the inclination of the deposit plate 31. The deposit plate 31 communicates with a funnel 38 which leads to a conduit 39 for directing the passage of the impurities to any suitable drain.

The tank 17 terminates in a communicating passage 40 which is inclined in a direction opposite to that of the bottom 18 of the tank 17 so that the submerged articles will be carried with the water therethrough for ultimate discharge in a container 41. This upward inclination maintains the water in the troughs 13 at a desirable head sufficient to carry the articles therethrough while being fully submerged. The container 41 is provided with a foraminous plate 42 disposed in a horizontal direction beneath the discharge orifice 43 of the passage 40; consequently the articles will be lodged on the foraminous screen to isolate the water therefrom. The water drains through the screen 42 to enable the repeated use thereof owing to a conduit 44 which connects the tank 41 with the low side of the pump 16.

The plates 30 are provided with brackets 45 near the extremities thereof to rest on guide rails 46 secured to the interior of the tank 17 so as to relieve the weight thereof from the conveyor links 29, it being noted that the brackets 45 engage the lower rails 47 on the top surface thereof to alleviate the weight throughout the length of the conveyor 28 regardless of its position. Suitable converging rods 48 have the extremities thereof in engagement with the shafts 24 and 25 to maintain them in spaced relation owing to the interposition of a rod 49 therebetween. The rod 49 projects through aligned bored bearings 50 provided at the point of convergence of the braces 48. The extremities of the rod 49 are threaded to receive nuts 51 and 52 on either side of the

bearings 50 so as to effectively support the shafts in their desired spaced relation.

In a modified embodiment of the invention, a tank or chamber 17' providing a level or horizontally disposed bottom 18' communicates with the inclined terminus of the trough 13^b. As shown, the trough terminus 13^b defines a restricted passage 20' with a wall 21' disposed at an inclination greater than the trough terminus 13^b. This effects a slight retardation which creates a water head in the troughs 13^a to insure the constant submersion and passage of the articles therewith.

Aligned pairs of sprocket wheels 26' and 27' are, in this instance, of the same diameter so that the conveyor 28' will traverse a path parallel to the bottom 18' of the tank 17'. The conveyor 28' preferably consists of interconnected links 29' arranged to form a pair 20 of endless chains 28^a and 28^b in mesh with the sprocket wheel peripheries to carry a series of uniformly spaced rods 54 therebetween for movement contra to the directional flow of the water in the tank 17'.

25 A plate 30' individual to each rod 54 is rigidly secured thereto in any suitable manner for travel in unison with the conveyor 28' parallel to the bottom 18' of the tank 17' in contact with the wall 21' to withdraw the 30 impurities existent in the tank 17' for discharge in a manner described in connection with the preceding embodiment.

The tank 17' terminates in a communicating passage constituting a pipe 40' which 35 rises vertically to a height beyond the level of the water in the tank 17' for termination below the bottom 18' of the tank 17' owing to a U-bend 55 provided therein intermediate the extremities thereof. The articles will 40 be carried therethrough for ultimate discharge in a container 41' which is provided with a foraminous plate 42' disposed in a horizontal direction beneath the discharge orifice 43' of the passage 40', thereby lodging 45 the articles on the plate 43' to isolate the water therefrom.

The pipe 40' is preferably of rectangular cross-section to receive a hinged valve 56 therein which is regulated by a slide bar 57 to control the discharge therethrough. Steam is injected in the pipe 40' below the bend 55 through a tube 58 which communicates with any suitable steam supply source. The injected steam assists the siphoning action 55 of the pipe 40' and further heats the water prior to its return to the troughs 13^a by means of the pump 16' in the manner described hereinabove. The steam injected heat enables the use of hot water which is 60 very much more effective as a cleansing expedient than cold fluids.

With the arrangement of parts above described it will be apparent that novel means have been provided to continuously withdraw impurities from a cleansing medium

which is used to process and blanch edible articles, such as peas, without requiring the manual manipulation thereof or interrupting the continuity of operation.

Various changes may be made in the embodiment of the invention herein specifically described without departing from or sacrificing any of the advantages thereof as defined in the appended claims.

I claim:

1. The combination with a trough, of movable means for directing articles along the bottom thereof, of means for maintaining a water flow therein to submerge the articles, said movable directing means skimming the impurities from the water without interruption to the articles, means for isolating the articles from the water, means for returning the water to said trough after the isolation of articles therefrom, and means for elevating the temperature of the water prior to the repeated use thereof and in the path of the water discharged from said trough, said temperature elevating means serving to accelerate the discharge of the articles from said trough.

2. The combination with means for directing articles along a predetermined path, of means for maintaining a water flow therein to submerge the articles, means for skimming the impurities from the water without interruption to the articles, siphon means for effecting the discharge of the articles, means for separating the water from the articles for repeated use, means for returning the water to said trough after separation of articles therefrom, and a steam injector within said siphon means and assisting the flow of water through said siphon means.

3. The combination with a trough, of means for directing articles along the bottom thereof, of means for maintaining a water flow therein to submerge the articles, means for skimming the impurities from the water without interruption to the articles, siphon means for effecting the discharge of the articles from the trough, said siphon means constituting a U-shaped pipe rising above said skimming means, means for separating the siphoned water from the articles for repeated use, means for returning the water separated from the articles to said trough, and a steam injector terminating within said U-shaped pipe to accelerate the discharge of the water from said siphon means and to concurrently elevate the water temperature, the stream from said injector mixing with the water in said siphon means as the water is discharged therethrough.
